PIPE CLIP

Eugene P. Moody, 308 S. 50th St.,
Philadelphia, Pa. 19143

Filed Dec. 3, 1965, Ser. No. 29

Term of patent 14 years

(Cl. D85—8)

Fig. 1

Fig. 2

Fig. 3

Fig. 4

FIG. 1 is a perspective view of a pipe clip showing my new design;

FIG. 2 is a front elevational view thereof;

FIG. 3 is a side elevational view thereof; and

FIG. 4 is a top plan view thereof.

The dominant feature of my design resides in the portions shown in full line.

I claim:

The ornamental design for a pipe clip, substantially as shown and described.
